US0D1111664S

(12) **United States Design Patent** (10) **Patent No.:** **US D1,111,664 S**
(45) **Date of Patent:** **** Feb. 10, 2026**

(54) **CONTAINER**

(71) Applicant: **Starbucks Corporation**, Seattle, WA (US)

(72) Inventors: **Cale Kaufman**, Seattle, WA (US); **Erin Malaspino**, Normandy Park, WA (US); **Mercedita Andrew**, Seattle, WA (US)

(73) Assignee: **Starbucks Corporation**, Seattle, WA (US)

(**) Term: **15 Years**

(21) Appl. No.: **29/891,725**

(22) Filed: **May 9, 2023**

(51) **LOC (15) Cl.** **07-01**

(52) **U.S. Cl.**

USPC **D7/510**; D7/512

(58) **Field of Classification Search**

(57) **CLAIM**

The ornamental design for a container as shown and described.

DESCRIPTION

FIG. 1 is a top perspective view of our new design for a container in an expanded condition.

FIG. 2 is a bottom perspective view of the container of FIG. 1.

FIG. 3 is a front view of the container of FIG. 1.

FIG. 4 is a back view of the container of FIG. 1.

FIG. 5 is a right side view of the container of FIG. 1.

FIG. 6 is a left side view of the container of FIG. 1.

FIG. 7 is a top view of the container of FIG. 1; and,

FIG. 8 is a bottom view of the container of FIG. 1.

The broken lines depict portions of the container that form no part of the claimed design. Portions of the container that do not include shading lines form no part of the claimed design.

1 Claim, 8 Drawing Sheets
